SLIDE VIEWERS

Richard G. Rideout, Cambridge, and John F. Herrmann,
Lynnfield, Mass.; said Herrmann assignor to said Ride-
out

Application August 25, 1955, Serial No. 37,665

Term of patent 14 years

(Cl. D61—1)

Fig. 1

Fig. 2

Fig. 1 is a perspective view of a slide viewer, showing our new design; and

Fig. 2 is a perspective view of the slide viewer similar to Fig. 1, but showing the opposite end thereof.

The dominant features of our design reside in the portions shown in full lines.

We claim:

The ornamental design for a slide viewer, substantially as shown and described.
